UNITED STATES PATENT OFFICE.

WILLIAM N. BEST, OF BROOKLYN, NEW YORK, ASSIGNOR OF ONE-FOURTH TO CECILIA WUPPER, OF BROOKLYN, NEW YORK.

SIGNAL-LAMP.

1,343,899.

Specification of Letters Patent. Patented June 22, 1920.

Application filed September 9, 1916. Serial No. 119,174.

To all whom it may concern:

Be it known that I, WILLIAM N. BEST, a citizen of the United States, and resident of New York, borough of Brooklyn, in the 5 county of Kings and State of New York, have invented certain new and useful Improvements in Signal-Lamps, of which the following is a specification.

This invention is an improvement in signal lights and has for its general object to better adapt signal lights of various forms and characters for use during daylight or under other conditions where the illumination from some other source of light decreases the contrast between the appearance 15 of the signal light in its turned-on and turned-off conditions.

In the common forms of colored signal lights, a sheet or plate of the desired color 20 is interposed between the source of light and the observer. This may be either a colored bulb inclosing the filament of an electric incandescent lamp, a colored sheet of celluloid or other transparent or translucent medium, 25 or it may be a separate glass plate, lens or bull's-eye in front of the electric, acetylene, oil, gas, or other illuminant. Such signal lights are open to certain objections due to the fact that the colored glass or other medium 30 is exposed to the view of the observer and appears of its characteristic color in the day-time or when illuminated from any source of light other than that of the light of the signal itself. When the signal is turned 35 on in the presence of some other source of illumination, the colored glass which the observer sees does not appear radically different from what it does when the signal is turned off. In both cases, it appears of the 40 same color although of course it is somewhat brighter when illuminated by the source of light of the signal itself. Often this difference in brightness resulting from the turning on or turning off of the signal light is 45 not noticed and therefore the signal fails in the accomplishment of its purpose. It is often difficult to tell whether a signal light is turned on or off when viewed from a distance during daylight.

50 Under many conditions of use, the colored glass is frequently broken so that the desired colored light rays are not given out when

the light is turned on and as a result, serious accidents are liable to occur.

In my improved signal light, I employ a 55 screen in the form of a diaphragm, sheet or plate between the colored medium and the observer, and of such a character that the colored medium is either entirely concealed from view, or so nearly concealed, that its 60 color is inconspicuous under all conditions of illumination from outside sources only. This interposed screen is so constructed that it will appear highly illuminated and of the desired color when the signal light is turned 65 on and the light rays pass from the source of light through the colored medium to the screen. Thus, the appearance of the signal light even in bright daylight is radically 70 different when the signal light is turned on from what it is when turned off. In one case, it is highly illuminated and brightly colored, while in the other case, it is dull and apparently opaque. The screen is of tough, flexible material so that it is not 75 liable to be cracked or broken and at the same time acts as a protector for the colored medium between it and the source of light. It is highly translucent when the light is 80 burning at the opposite side but is sufficiently opaque to prevent the light or colored medium from being seen when the light is turned off.

My invention may be incorporated in signal lights employed for a great variety of 85 purposes. For instance, it may be used to great advantage on automobiles to indicate to pedestrians or drivers of other vehicles that the vehicle carrying the signal is about to stop or turn to the right or left.

90 A system in which my improved signal light may be used to advantage is that disclosed in my Patent No. 1,192,264, granted July 25, 1916. In such an installation, the appearance of the signal light when turned on at night would be different from the ordinary side or tail light and in the day time, it could be used equally well as at night for the change in color of the screen when the light is turned on could be easily and instantaneously noticed by those for whose benefit the signal is operated.

95 My improved signal light may also be used in connection with railroad semaphore,

switch, and other signals, or on light houses, and may be used with constant, intermittent lights controlled manually or automatically and revolved, oscillated or held stationary.

5 As previously indicated, the source of light may be of any kind suited for the particular purpose at hand.

Reference is to be had to the accompanying drawings in which I have illustrated 10 only a few of the various specific forms which my invention may assume. In these drawings,

15 Figure 1 is a face view of a signal light constructed in accordance with my invention, a portion of the screen being broken away;

Fig. 2 is a central longitudinal section on the line 2—2 of Fig. 1;

20 Fig. 3 is a partial side elevation and partial section of a different form, and

Figs. 4 and 5 are plan and edge views, respectively, of a portion of a suitable screen and on a somewhat enlarged scale.

In the specific form shown in Figs. 1 and 25 2, I employ an incandescent electric filament as the source of light, the said filament being inclosed in the ordinary vacuum bulb 10. This bulb is shown as properly positioned in respect to a parabolic reflector 11 which latter is supported in a suitable case 12. The lamp is of a general form 30 commonly employed on automobiles and may be mounted or supported in any suitable manner.

35 In front of the bulb I place a screen 13 in addition to or in place of the ordinary lens, glass plate or bull's-eye. This screen is preferably slightly elastic, highly flexible, comparatively tough and unaffected by the 40 heat of the lamp or the action of the weather. It may be made of various different compounds, but a suitable one is formed of a gelatinous or gummy substance such as gelatin, or glue, to which is added glycerin 45 and formaldehyde. Upon boiling this mass to evaporate the water, the remaining mass may be rolled into sheets suitable for my purpose although an additional coating of waterproofing material may be applied thereto if desired. A sufficient amount of 50 coloring matter is incorporated in the substance so as to render the sheet sufficiently opaque to prevent the bulb within the lamp from being seen.

55 If the sheet is to be used as the front of the lamp and separate and independent of any glass plate, the sheet may, if desired, be reinforced to better enable it to withstand the effect of pebbles or other objects 60 striking against it. Such a reinforcement might be formed of a very coarse mesh of very thin wires 14 as indicated in Figs. 4 and 5.

In order to get a uniform distribution of 65 light over the surface and to increase the

brilliancy, one surface of the screen may be provided with thin corrugations 15 as indicated in Fig. 5.

To get the desired color effect when an electric light is employed, it is not necessary to employ a color screen separate from the body of the electric light itself. The bulb may be colored red, green or any other color desired for signaling purposes and when the current is turned on, the effect 75 of this colored bulb in the rear of the screen will be to highly illuminate the latter and make it appear the same in color as the bulb.

Under some circumstances, it may be desired to illuminate a portion of the screen with one color and another portion of the screen with another color. As shown, the upper half of the bulb is coated green while the lower half is coated red so that the action of the parabolic reflector will be to give the appearance of corresponding colors on the upper and lower halves of the screen when the light is turned on. When the light is turned off, the opacity of the screen 90 prevents either the red or the green of the bulb from being seen.

The screen may be secured in place in any suitable manner. As shown, I employ a collar 16 held in place by suitable screws 17 95 and coöperating with a peripheral flange on the casing to form clamps for the peripheral portion of the screen.

As I have previously indicated, my invention is not dependent upon any particular character of illuminant nor any particular form of lamp body. In Fig. 3, I have shown a lamp casing 18 having a curved mirror 19 at the back and in the rear of an acetylene burner 20. At the front 105 of the casing is a door 21 serving to support a screen 22 and a colored medium 23. The screen may be of the same character as that heretofore described. The colored medium 23 may be in the form of a glass 110 plate constituting the equivalent of the glass bulb of Figs. 1 and 2 so far as the production of the desired colored light rays is concerned. This glass plate 23 may be colored red, green, or any other desired 115 shade and may have different parts of different colors, or may have letters, figures, arrows, symbols, or other indications of a color contrasting with that of the balance of the plate. The colored plate and screen 120 may be supported closely adjacent to each other or spaced slightly apart and may be clamped in any desired or suitable manner. As shown, the periphery of the screen is held between an inturned flange 24 on the 125 closure 21 and a clamping ring 25. The colored glass 23 is shown as having its periphery supported in a U-shaped collar 26 which may be soldered or otherwise held in place in the closure 21.

The forms hereinbefore described are merely examples of my invention and I wish it understood that they are to be considered merely in an illustrative and not in 5 a limiting sense.

Having thus described my invention, what I claim as new and desire to secure by Letters Patent is:

1. A signal lamp comprising a casing, 10 signaling means within the casing, including a source of light and a colored medium, and a shield arranged in front of the signaling means and consisting of a tough substantially non-breakable, uniformly translucent flexible sheet adapted to protect the signals from being injured by missiles to 15 obliterate the color of the said medium when the light of the signaling means is ex-

tinguished whereby the unlighted signal will be prevented from showing color when 20 exposed to exterior light.

2. A signal lamp provided with a shield constituting a front wall for the signal and consisting of a tough substantially non-breakable, uniformly translucent flexible 25 sheet adapted to obliterate color when the signal lamp is extinguished to prevent the unlighted signal lamp from showing a signal when exposed to exterior light, said shield being also adapted to protect the 30 signal lamp from being injured by missiles.

Signed at New York, in the county of New York and State of New York, this 8th day of September, A. D. 1916.

WILLIAM N. BEST.
